UNITED STATES PATENT OFFICE

LEO T. LE FEBURE, OF CEDAR RAPIDS, IOWA, ASSIGNOR TO LE FEBURE LEDGER COMPANY, OF CEDAR RAPIDS, IOWA, A CORPORATION OF IOWA

BINDER TRAY

Application filed November 16, 1925. Serial No. 69,346.

This invention is designed to improve what is ordinarily known as tray binders which are used with bookkeeping systems. Such binders have heretofore been made having a platform or base over which the jaws operate. With the present invention this base is supplied with a box extending up from the base, thus more certainly protecting the records in this type of binder and also providing a convenient means in which such records may be entirely enclosed if desired. Features and details of the invention will appear from the specification and claims.

The invention is illustrated in the accompanying drawings as follows:—

Fig. 1 is a perspective view of the tray.

Fig. 2 is a longitudinal section through the device with the cover in place.

Fig. 3 is a perspective view of one of the corners with the corner portion broken away to better show construction.

Fig. 4 is a cross section on the line 4—4 in Fig. 2.

1 marks the base of the tray. This is provided with the usual slot 2 in which there is arranged an adjusting screw 3. The adjusting screw 3 is carried in bearings 3^a and 3^b and is adapted to be operated by a crank 3^c at the outside of the end of the tray. A nut 4 is arranged on the screw 3 and this is secured to a jaw frame 5 carrying a jaw 6 by means of pivotal connections 7. A rod 8 extends from the bearing 3^a to a support 9 in the frame and a sliding block 10 is arranged on the rod 8. A jaw frame 11 is secured to the block and a tilting jaw 13 is secured to the frame by pivots 14. A screw 12 is arranged in the block 10 and adapted to clamp the block in adjustment on the rod 8.

40 The base is supplied with box walls extending entirely around the base, these being formed with the ends 15 having terminal angle portions 16 extending along the sides, the angles being secured to the base by screws 17. This extension along the sides stiffens or makes rigid the connection between the base and the ends.

45 Sides 18 are connected by hinges 19 with the movable side supports 20, these side supports being secured to the base by screws 21 ex-

tending through slots 22. The upper edges of the sides 18 have the bent over inturned edge 23 which is adapted to hook over the top of the angle portions 16 of the ends. This is accomplished by lifting the sides slightly as they are swung to place and allowing the hook 23 to move downwardly over the upper edge of the inturned corner 16, the screw and slot connection 21 and 22 permitting this upward movement of the sides and the sides may be 55 disengaged by a reverse of this movement.

50 A swinging bail acting as offset rail 23 is hinged at 24 to the angle portion 16 of each of the ends. Its offset portion as shown swings outwardly with the opening of the side. 65 When at its outer position it rests on a shoulder 16^a on the angle portion 16. When the side is moved up to position the bail is swung up with the side. If the out-bend of the bail is more offset than desired the rod 3 may be 70 made directly in line with the sides with the same mounting.

55 A guide rod 25 extends over the base. It has a slotted end 26 which extends over flanges 27 on the inner faces of the ends. The rod is 75 slidingly mounted on the flanges and locked in adjustment thereon by screws 28 extending through the rods against the flange.

60 If desired a cover 29 may be mounted on the walls of the box making a complete enclosure of the records carried by the tray. This cover may be locked in the usual manner of covers. The cover rests on the end walls. The edge slightly telescopes the side walls preventing the opening of the side walls when 85 the cover is in place.

65 It will be noted that in the present structure a tray binder is provided having the advantage of the ordinary flat board tray binder in which there is perfect freedom for the operator in offsetting the material; that the binder is provided with a normally stationary jaw which, however, may be adjusted to accommodate the normal volume of cards used; that the binder is provided with a movable jaw operating in the manner of the usual tray binder for locking the cards, or book, as it may be called in closed position and that this movable jaw is operable from without the binder so that if the binder cover has 95 100

been put in place in temporary intervals between use as where one binder is substituted for another in the day's use the cards of the binder may be set up and clamped between 5 the normally stationary jaw and the movable jaw through the adjustment or operation of the movable jaw and this can be accomplished without opening the tray, or removing the cover.

10 What I claim as new is:—

1. In a binder tray, the combination of a base; a movable jaw on the base; box walls extending upwardly from the base; flanges extending inwardly from the end walls; and 15 a guide rod extending longitudinally across the base and mounted on said flanges.

2. In a binder tray, the combination of a base; a movable jaw on the base; box walls extending upwardly from the base; flanges 20 extending inwardly from the end walls; and a guide rod extending across the base and mounted on said flanges, said guide rod having slots engaging the flanges, said slots permitting the sliding of the rod on the flanges 25 for adjustment.

3. In a binder tray, the combination of a base; jaws on the base; box walls extending upwardly from the base; and a hinged connection between one side wall and the 30 base permitting the swinging outwardly of the side wall, said side wall having detachable interlocking connections between the same and the end walls.

4. In a binder tray, the combination of a 35 base; jaws on the base; box walls extending upwardly from the base; and a hinged connection between one side wall and the base permitting the swinging outwardly of the side wall, said hinge connection comprising 40 a movably mounted hinge support, and an interlocking connection between the hinged side wall and the end walls moving into engagement by the moving of the hinge support.

45 5. In a binder tray, the combination of a base; jaws on the base; box walls extending upwardly from the base; and a hinged connection between one side wall and the base permitting the swinging outwardly of the side wall, said hinge connection comprising 50 a movably mounted hinge support, and a hook on the upper edge of the side wall adapted to hook over the end wall of the box.

55 6. In a binder tray, the combination of a base; jaws mounted on the base, one of which being movable; box walls extending upwardly from the base; means operable from without the walls adjusting the movable jaw; 60 and a cover resting on a portion of the walls and enclosing the jaws.

7. In a binder tray, the combination of a base; jaws mounted on the base, one of which being movable; box walls extending 65 upwardly from the base, the side walls there-

of being hinged to the base; means operable from without the walls adjusting the movable jaw; and a cover resting on the end walls and enclosing the jaws, the cover telescoping the side walls and locking them in place.

8. In a binder tray, the combination of a base; box walls extending upwardly from the base; a movable jaw arranged on the base, said jaw being arranged within the walls; a hinge connection between one side wall and the base permitting the swinging outwardly of said side wall; and an offset rail swingingly mounted and movable outwardly after the opening of the side wall, or inwardly to permit the closing of the side wall.

75 9. In a binder tray, the combination of a base; box walls extending upwardly from the base; a movable jaw on the base; a hinge connection between one side wall and the base permitting the swinging outwardly of 80 said side wall; and an outwardly bent bail forming an offset, said bail being hinged on the end walls and adapted to swing outwardly after the opening of the side wall or inwardly to permit the closing of the side wall.

10. In a binder tray, the combination of a base; box walls extending upwardly from the base; a movable jaw on the base; a hinge connection between each side wall and the 95 base permitting the swinging outwardly of the side walls; and an offset rail along one of the side walls, said offset rail being adjustable to a position outside of the line of said side wall after the wall is opened and 100 enclosed within the walls when the side wall is closed.

In testimony whereof I have hereunto set my hand.
